EXCAVATING TOOTH

Gerald A. M. Petersen, Santa Clara, Calif.

Application January 31, 1956, Serial No. 39,974

Term of patent 14 years

(Cl. D41—1)

FIG. 1

FIG. 2

FIG. 4

4

FIG. 3

4

Fig. 1 is a perspective view of an excavating tooth, showing my new design.

Fig. 2 is a plan view of the same as seen from above in Fig. 1.

Fig. 3 is a side elevational view.

Fig. 4 is a rear elevational view of the excavating tooth as seen from line 4—4 in Fig. 3.

I claim:

The ornamental design for an excavating tooth substantially as shown.
